(57) **CLAIM**

The ornamental design for a magnetic building block set, as shown and described.

DESCRIPTION

FIG. 1 is a front perspective view of a magnetic building block set, showing our new design;

FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a front perspective view of another embodiment;
FIG. 9 is a front view thereof;
FIG. 10 is a rear view thereof;
FIG. 11 is a left side view thereof;
FIG. 12 is a right side view thereof;
FIG. 13 is a top view thereof;
FIG. 14 is a bottom view thereof;
FIG. 15 is a front perspective view of another embodiment;
FIG. 16 is a front view thereof;
FIG. 17 is a rear view thereof;
FIG. 18 is a left side view thereof;
FIG. 19 is a right side view thereof;
FIG. 20 is a top view thereof;
FIG. 21 is a bottom view thereof;
FIG. 22 is a front perspective view of another embodiment;
FIG. 23 is a front view thereof;
FIG. 24 is a rear view thereof;
FIG. 25 is a left side view thereof;
FIG. 26 is a right side view thereof;
FIG. 27 is a top view thereof;
FIG. 28 is a bottom view thereof;
FIG. 29 is its split state diagram;
FIG. 30 is a front perspective view of another embodiment;
FIG. 31 is a front view thereof;
FIG. 32 is a rear view thereof;
FIG. 33 is a left side view thereof;
FIG. 34 is a right side view thereof;
FIG. 35 is a top view thereof;
FIG. 36 is a bottom view thereof;
FIG. 37 is its split state diagram;
FIG. 38 is a front perspective view of another embodiment;
FIG. 39 is a front view thereof;
FIG. 40 is a rear view thereof;
FIG. 41 is a left side view thereof;
FIG. 42 is a right side view thereof;
FIG. 43 is a top view thereof;
FIG. 44 is a bottom view thereof;

FIG. 45 is its split state diagram;
FIG. 46 is a front perspective view of another embodiment;
FIG. 47 is a front view thereof;
FIG. 48 is a rear view thereof;
FIG. 49 is a left side view thereof;
FIG. 50 is a right side view thereof;
FIG. 51 is a top view thereof;
FIG. 52 is a bottom view thereof;
FIG. 53 is its split state diagram;
FIG. 54 is a front perspective view of another embodiment;
FIG. 55 is a front view thereof;
FIG. 56 is a rear view thereof;
FIG. 57 is a left side view thereof;
FIG. 58 is a right side view thereof;
FIG. 59 is a top view thereof;
FIG. 60 is a bottom view thereof;
FIG. 61 is its split state diagram;
FIG. 62 is a front perspective view of another embodiment;
FIG. 63 is a front view thereof;
FIG. 64 is a rear view thereof;
FIG. 65 is a left side view thereof;
FIG. 66 is a right side view thereof;
FIG. 67 is a top view thereof;
FIG. 68 is a bottom view thereof;
FIG. 69 is its split state diagram;
FIG. 70 is a front perspective view of another embodiment;
FIG. 71 is a front view thereof;
FIG. 72 is a rear view thereof;
FIG. 73 is a left side view thereof;
FIG. 74 is a right side view thereof;
FIG. 75 is a top view thereof;
FIG. 76 is a bottom view thereof;
